UNITED STATES PATENT OFFICE

2,281,245

RAILWAY CAR

Peter Parke and Nils A. Thunstrom, Chicago, Ill.,
assignors to The Pullman Company, Chicago,
Ill., a corporation of Illinois

Application August 9, 1938, Serial No. 223,963

5 Claims. (Cl. 105—414)

The present invention relates to a railway passenger car of the duplex or double decker type which is provided with a plurality of bedrooms arranged at two different levels, one above the other. The upper rooms overlap in part those on the lower level, and in fact utilize portions of the head room of the lower rooms. Each room is for single occupancy in that the upper berth is eliminated and provides for maximum comfort alike to the passengers, whether they be traveling in the upper or the lower rooms.

In this car, as in other cars, the railway mail specifications require that all buff and draft loads shall be figured as being carried by the longitudinal members positioned below the floor level, and certain car builders, as a matter of practice, calculate the center sill alone to carry these loads. Although these specifications were drafted for use in designing mail cars, the general practice is to apply them to passenger cars as well.

In order to have as light a member as possible and yet one having sufficient strength to carry the buff and draft loads, it is necessary to so position the center sill that the line of buff and draft will lie substantially along the horizontal line passing through the centers of gravity of the various center sill cross-sections throughout the length of the sill. For the sake of convenience this horizontal line will be referred to as the longitudinal axis of the center sill, and in order to eliminate eccentricity this axis should be substantially a straight line. Any deviation of this axis from a straight line results in the production of eccentricity in the end loading on the center sill, thereby producing a bending moment in the center sill. This condition requires the use of additional material in the center sill which adds weight to the car.

In many cars the lines of buff and draft do not coincide, because the buffering loads are carried partly through the buffers positioned on the end sills and partly through the couplers, while the draft loads are transmitted entirely through the couplers. In these cars it is desirable to have the line of buff very nearly correspond with the longitudinal axis of the center sill.

It is desirable to increase the distance between the floor and the roof of the car in order to provide adequate head room in the lower and upper rooms. One way to provide this head room would be to depress the center sill along with the other longitudinal framing members in the underframe, thereby lowering the floor, but the increased stresses caused by the eccen-

tric loading of buff and draft forces would necessitate adding metal in the center sill, thereby increasing its weight. The present-day demand for lighter weight equipment makes this undesirable.

Among the principal objects of the present invention, then, are the following: To provide a railway car of the duplex type having adequate head room for both the lower and upper rooms, and having a center sill adapted to carry buff and draft loads with a minimum of eccentricity in the application of such loads.

Other objects and advantages will become apparent as the disclosure proceeds and the description is read in conjunction with the accompanying drawings, in which

Fig. 1 is a diagrammatic plan view showing the general floor plan arrangement of the rooms and the aisle, only the portion of the car from approximately its center to the non-articulated end being shown;

Fig. 2 is a diagrammatic plan view showing the general floor plan arrangement from approximately the center of the car to the articulated end. This figure completes the showing of Fig. 1;

Fig. 3 is a diagrammatic view in side elevation, showing the general arrangement of the upper and lower bedrooms;

Fig. 4 is a fragmentary plan view of the car underframe, showing the portion from approximately the center of the car to the vestibule or non-articulated end;

Fig. 5 is a fragmentary plan view of the car underframe showing the portion from approximately the center of the car to the articulated end. This figure completes the showing of Fig. 4;

Fig. 6 is a fragmentary side elevational view of the portion of the underframe included in Fig. 4;

Fig. 7 is a fragmentary side elevational view of the portion of the underframe included in Fig. 5;

Fig. 8 is a vertical longitudinal sectional view of the portion of the underframe shown in Fig. 4, and is taken on the line 8—8 of Fig. 4;

Fig. 9 is a vertical longitudinal sectional view of the portion of the underframe shown in Fig. 5, and is taken on the line 9—9 of Fig. 5;

Fig. 10 is a transverse sectional view of the car underframe taken at the bolster along the line 10—10 of Fig. 4, and shows portions of the side posts and the method of tying them into side sills;

Fig. 11 is a transverse sectional view of a por-

tion of the underframe, taken at one of the needle beams on the line 11—11 of Fig. 5;

Fig. 12 is a transverse sectional view of a portion of the underframe, showing the jacking beam and taken on the line 12—12 of Fig. 5.

Fig. 13 is a transverse sectional view of the car taken at substantially its center portion, and shows in broken lines a portion of the car interior equipment;

Fig. 14 is a fragmentary transverse sectional view of the car taken in the region of the trucks, showing the relationship between the center sill and the side sills and floor stringers in this region;

Fig. 15 is an enlarged fragmentary plan view of the underframe at the non-articulated end of the car showing the coupler mechanism; and

Fig. 16 is a longitudinal sectional view through the portion of the underframe shown in Fig. 15, the view being taken on the line 23—23 of Fig. 15.

A specific embodiment of the present invention is selected for the purpose of disclosure only, in compliance with Section 4888 of the Revised Statutes, and the appended claims are not to be limited by this particular disclosure but are to be construed as broadly as the prior art will permit.

General organization

Referring to Fig. 3, a car body is shown supported on a pair of trucks 26, 27. For the purpose of illustration, the car is articulated at one end and non-articulated at the other end. Obviously the invention is equally applicable to a completely articulated car, or to one which is wholly non-articulated. To aid the description we will refer to the non-articulated end of the car as the A end, and the articulated end of the car as the B end.

At the A end the car body is provided with a vestibule 28 (Fig. 1) of the usual type, having door openings at 29 and 30 which are closed by the usual doors 31 and 32. Steps (not shown) are furnished to permit passing to and from the car, and trap doors 33 and 34 cover up the steps and finish out the floor of the vestibule 28. At the B end of the car body a passage 35 permits communication between the present car and an adjoining car. There are no outside doors at this latter end. Doors 36, 37, are provided at the A and B ends, respectively, of the car, and are hinged to end framing members and permit passage to and from the car interior.

In a further effort to simplify the description of the particular embodiment of the present invention the side of the car, indicated by the letter C, will be referred to as the bedroom side, and the opposite side, indicated by the letter D, will be referred to as the aisle side.

Extending throughout the length of the car is an aisle 38, which passes along the aisle side of the car. The bedrooms are positioned entirely along the bedroom side of the car, and open onto the aisle 38. In the particular embodiment chosen, duplex rooms are positioned in the region between the trucks, as shown in Fig. 3, and over the truck at the A end of the car a pair of bedrooms 39, 40, are provided, both being on the same level and having a communicating door 41 and a sliding partition 42 separating them. Between the room 39 and the A end of the car is a lavatory 48, having the usual hopper 49, washstand 50, and dressing shelf 51. A door 52 gives access to the lavatory. Also at this end is positioned a porter's seat 53.

Further along the car, toward the center, is

an upper room 43, separated from the room 40 by a solid wall 44. From this point to the region over the truck on the B end of the car are a plurality of duplex rooms. Over the articulated truck are an upper room 46, a locker 47 for housing equipment and porter's supplies, and a locker 55 for housing electric panels, switches, etc.

The duplex rooms are indicated at 56 to 61, inclusive, 43 and 46, and are arranged in most part in pairs, as, for example, 56 and 57, with a partition 68 separating the two. This partition is provided with a communicating door 69 (see Fig. 1), and a sliding partition 70 adapted to be pushed into a recess between spaced panels 71, 72, making up the stationary portion of the partition 68. When it is desired to provide communication between two adjoining bedrooms, such as rooms 56 and 57, the door 69 may be swung back into one of the rooms, as, for example, room 56, against the outside door 73, thus closing off this latter door but giving access to an outside door 74 from either of the bedrooms 56 or 57. If it is desired to open the partition 68 still further, sliding partition 70 may be pushed back into the recess between the panels 71 and 72.

The upper rooms also are arranged, in most instances, in pairs, as, for example, rooms 58 and 59, and stairs 76, together with outside doors 77, 78, afford access to these adjoining rooms. A partition 79 separates adjoining upper rooms, and a communicating door 80 places them en suite. This door is the only movable part of the partition 79.

Each of the rooms is provided with a couch 81, which extends transversely of the car and is made into a bed for night use, a hopper 82, and a washstand and other toilet facilities, indicated at 83.

Framing in general

Referring to Figs. 4, 5 and 13, the framing generally consists of an underframe 90, a pair of side frames 91 and 92, end frame 93 at the articulated end, a body end frame 94, and a vestibule buffer wing 95 at the non-articulated end of the car, and a top frame 96.

Underframe

Extending longitudinally of the car throughout its length is a center sill 97, made up of a pair of Z-bars 98, 99, welded together at the top, as indicated at 100. This sill extends from the vestibule buffer wing 95 to the end frame 93, and through its entire length has a longitudinal axis which is substantially a straight line. This feature is very desirable, since the center sill is the main buff and draft load-carrying member, and with this axis lying substantially along the line of buff and draft there is a minimum of eccentricity in the application of such loads. This fact greatly reduces the stressing of the center sill, and permits the use of a lighter member.

Positioned at the sides of the car are a pair of side sills 101, 102, which, as shown, are angle bars, and extending transversely of the car between the side sills are a plurality of cross-bearers consisting of a body bolster 103 which supports the car body on the truck at the non-articulated end, a pair of deep cross-bearers 104, 105 (sometimes referred to as needle beams), which serve to unload the stresses from the center sill and carry them into the side frames, and a jacking beam 106 which is provided with a pair of jacking pads 107, one positioned at each end of the beam (see Fig. 12). In addition to

these transverse members there are a plurality of shallow cross-bearers 108 (sometimes referred to as cross ties), which extend between the center sill and the side sills, and support the floor and equipment mounted on the under side of the car. Extending longitudinally of the car is a pair of floor stringers 109, 110, resting on the shallow cross-bearers, as shown in Fig. 14, and on top of these floor stringers is mounted the flooring 111.

As shown in Fig. 10, floor stringers 113 and 114 extend over the center sill with their top flanges and the top flanges of stringers 109 and 110 lying in the same plane. The flooring 111 rests on top of these flanges, and in the regions over the trucks is positioned approximately four feet three inches above the rails, which is the more or less conventional floor height.

The stringers 113, 114, 109 and 110 are provided with downward inclinations at 115 (see Figs. 6 to 9 inclusive) toward the level of the top surface of the center sill, and stringers 113 and 114 continue as flattened Z-bars throughout the region between the trucks, as shown in Fig. 13, so that in this region the floor level is lowered approximately six inches. The side sills 101 and 102 also are depressed between the trucks.

Over the trucks the shallow cross-bearers 108 extend through the Z-bars 113, 114, respectively, resting upon the center sill (as best shown in Fig. 14), and are secured at their other ends to side sills; while in the central region between the trucks these cross-bearers are secured to the sides of the center sill by means of brackets 116, to which are riveted the cross-bearers, as indicated at 117.

The jacking beam 106 (see Fig. 12) is made up of a web portion 118, a top flange 119 which extends from side sill to side sill passing over the center sill, and bottom flanges 120 which terminate at 121 and are welded to the center sill, as shown at 122. A reinforcing plate member 122 joins the two bottom flanges 120, and is secured by rivets 123 to these flanges. A vertically extending web 124 is placed between the bottom flange 120 and the top flange 119, directly over the jacking pad 107, and is welded in place, as indicated at 125. The floor stringers 109, 110, are riveted to the jacking beam by means of brackets 126. It is to be understood that one of these jacking pads, 107, is positioned on each end of the jacking beam, and that the structure of the jacking beam on both sides of the center sill is identical.

The deep cross-bearers 104, 105 (see Fig. 11) comprise a pair of webs 127, one placed on each side of the center sill, and a flange 128 completely surrounds each of the webs 127. The floor stringers 109, 110, are riveted to the cross-bearers by brackets 134, and a reinforcing plate 129 joins and is secured to the bottom flanges of the webs 127.

All of the various longitudinal members tie into the end sill 130 at the articulated end in some suitable manner, as shown in Fig. 5, and into the vestibule end sill 131 at the non-articulated end in the case of the center sill, as best shown in Fig. 4, and into the body end sill 132 in the case of the other longitudinal members. A pair of longitudinal members 169 extend from the vestibule end sill 131 to the body end sill 132, and each is suitably secured in place.

The spacing of the shallow cross-bearers 108 depends largely upon the weights and location of the various pieces of equipment to be supported,

for example, heavy equipment will normally require close spacing of the shallow cross-bearers, as indicated in Fig. 5.

Because of the extremely low floor level between the truck regions it is often difficult to find room for mounting of equipment, and consequently provision must be made in the underframe to increase available room. In Fig. 4 it will be seen that to the right of the deep cross-bearer 104 a portion of the floor stringer 110 has been moved toward the center sill so as to provide a large opening 133 for receiving some large piece of equipment.

An attempt has been made to indicate in the drawings and description where the various members are attached, and many riveted joints have been shown in the drawings. It is to be understood, however, that the number of rivets required at each joint is not accurately shown. Welding has been used to a great extent in securing together many of the members, and, of course, may be used in a great many places other than those shown.

The floor 111 may be made up of layers of cork or other suitable material placed on conventional flooring, and is supported on floor stringers, as best shown in Figs. 13 and 14. Along the sides of the floor truss planks 185 are placed between the floor and the side wall, and extend the full length of the car body, projecting below the flooring. These planks are flanged inwardly at 186, thus providing a seal for the floor along the sides of the car.

Floor supports 187, having flanges 188 engaging the flanges 186 of the truss planks 185, extend upwardly from and are secured to the vertical flanges 189 of the side sills.

Projecting downwardly from the sides of the car are skirts 190, indicated in broken lines in Fig. 13, and they are provided with stiffening flanges 191 and are supported from the underframe by means of skirt supports 192. Flanges 193 extend along the top of the skirts for riveting purposes.

Referring to Figs. 4, 15, and 16, coupling mechanism, generally indicated at 194, is provided for fastening the car to an adjoining car at the non-articulated ends thereof. The specific details of this coupling mechanism do not constitute part of the present invention, and for that reason only a general, brief description will suffice. The coupler itself is shown at 195 (Fig. 15), and extending rearwardly from the coupler head 195 is a coupler shank 196. The center sill 97 of the car underframe is spread adjacent to one end thereof, as indicated at 97', and the coupler 195 with its shank 196 is supported between these spread portions 97' of the center sill. A draft gear arrangement, generally indicated at 197, is provided at the rear end of the coupler shank. This draft gear is adapted to take up shocks exerted on the coupler head 195 due to the transmission of forces through the coupler and is fastened to the center sill 97 of the underframe in some suitable manner to transfer forces from the shank 196 of the coupler into the center sill. Arms 198 are provided on each side of the shank 196 of the coupler, and by means of springs 199 these arms 198 tend to hold the coupler normally in its central position shown in Fig. 15. A coupler supporting member 200 is arranged to support the free end of the coupler. The present coupler arrangement is very similar to the one shown in the patent to Andrew Christianson No. 2,149,840, dated March 7, 1939. This patent clearly and

completely discloses the details of construction and operation of a tight-lock coupler of the type illustrated in the present application.

We claim as our invention:

1. A railway car of the class described mounted on trucks and having an underframe including a center sill extending throughout the length of the car, the longitudinal axis of which is substantially a straight line, means at the ends of the car for receiving the buff and draft loads, the relative positions of the center sill and said means being such that the longitudinal axis of the center sill will be substantially along the line of buff and draft applied at said means, car side sills lying substantially in the horizontal projection of the center sill in the region between the car trucks and positioned above the horizontal projection of the center sill in the region over the trucks, and a floor supported on the side sills throughout their length and also supported on and spaced above the center sill adjacent to the trucks.

2. A railway car mounted on a pair of trucks and having an underframe which includes a center sill whose longitudinal axis throughout its length is substantially a straight line, body side sills lying within the horizontal projection of the center sill in the region between the trucks and positioned at a higher elevation with respect to the center sill in the regions over the trucks, and a floor supported on the side sills throughout their length and spaced above the center sill adjacent to the trucks.

3. A railway car mounted on trucks and having an underframe including a buff and draft load-carrying member which is positioned longitudinally of the car and whose resultant longitudinal axis is substantially a straight line, the position of said member being such that the longitudinal axis is substantially in line with the line of buff and draft, a longitudinal member on

each side of the buff and draft load-carrying member and extending the full length of the car, each of said longitudinal members lying substantially in the horizontal projection of the buff and draft loading-carrying member in the region between the car trucks and projecting above the horizontal projection of said load carrying member in the region over the trucks, and a floor supported on said supporting members throughout their length and also supported on and spaced above the center sill adjacent to the trucks.

4. In a railway car having a pair of trucks, an underframe comprising a center sill extending the full length of the car and whose longitudinal axis is substantially a straight line, a pair of side sills lying substantially in the horizontal projection of the center sill in the region between the trucks and being raised to a higher elevation in the region above the trucks and floor stringers disposed with their upper edges above and closely adjacent to the plane of the top of the center sill in the region between the trucks and with their upper edges space above the plane of the top of the center sill in the regions over the trucks.

5. A railway car mounted on trucks and having an underframe including a buff and draft load-carrying member which is positioned longitudinally of the car and whose resultant longitudinal axis is substantially a straight line, a longitudinal member on each side of the buff and draft load-carrying member and extending the full length of the car, transverse floor supporting members supported on said longitudinal members and disposed below the top of the buff and draft load-carrying member in the region between the trucks and on top of said load-carrying member in the regions adjacent to the trucks.
